ABSTRACT OF THE DISCLOSURE

Compounds comprising disubstituted acyl amide oximes with one of the substituents being 5-nitro-2-furyl. These compounds are useful as antibacterial and antifungal agents.

This application is a continuation-in-part of U.S. application Ser. No. 640,343, now abandoned, filed May 22, 1967, which is a continuation-in-part of U.S. application Ser. No. 532,571, filed Mar. 8, 1966, now abandoned, which is a divisional application of U.S. application Ser. No. 314,849, filed Oct. 9, 1963, now U.S. Pat. 3,272,828.

SUMMARY

This invention relates to compounds of the formula

In this formula, when R_1 is 5-nitro-2-furyl, R_2 represents hydrogen, loweralkyl, haloloweralkyl of from 5-17 carbon atoms.

phenyl,
aralkyl,
aryloxyloweralkyl,
loweralkylaminoloweralkyl,
dialkylaminoloweralkyl,
carboxy,
carboloweralkoxy,
carboloweralkoxyloweralkyl,
carboxamidoloweralkyl,
acylaminoloweralkyl,
halophenyl,
alkoxyphenyl,
hydroxyphenyl,
cyanoloweralkyl,
acylaminophenyl,
loweralkylthiophenyl,
nitrophenyl,
aminophenyl,
sulfonamidophenyl,
nitrophenylloweralkyl,
halophenylloweralkyl,
loweralkylphenyl,
diloweralkoxyphenylloweralkyl,
loweralkylhalophenyl

loweralkylphenyl, N-acyl-N-cycloalkylaminoloweralkyl, N-acyl-N-loweralkylaminoloweralkyl, N-acyl-N-phenylaminoloweralkyl, N-acyl-N'-diloweralkylaminoloweralkylaminoloweralkyl, haloacylaminoloweralkyl, N,N-dialkyl-N-(arylloweralkyl)-loweralkyl ammonium chloride, N,N-dialkyl N-(dihaloarylloweralkyl)lower alkyl ammonium chloride, morpholinoloweralkyl, piperidinolower alkyl

pyrrolidinoloweralkyl and α -halomethylphenyl;

and when R_2 is 5-nitro-2-furyl, R_1 represents halolower-alkyl of from 5-17 carbon atoms,

5 halophenyl,
nitrophenylloweralkyl,
halophenylloweralkyl,
acylaminophenyl,
loweralkylphenyl,
10 diloweralkoxyphenylloweralkyl,
loweralkylhalophenyl,
diloweralkylaminoloweralkyl,
acylaminoloweralkyl,
N-acyl-N-cycloalkylaminoloweralkyl,
15 N-acyl-N-loweralkylaminoloweralkyl,
N-acyl-N-phenylaminoloweralkyl,
N-acyl-N-diloweralkylaminoloweralkyl,
haloacylaminoloweralkyl,
acylthioweralkyl,
20 morpholinoloweralkyl,
piperidinoloweralkyl,
pyrrolidinoloweralkyl, and
 α -halomethylphenyl.

The terms "loweralkyl" and "loweralkoxy" include the straight and branched alkyl and alkoxy radicals containing from one to seventeen carbon atoms, inclusive, except as otherwise indicated. The term "cyclo" includes rings of from three to seven carbon atoms.

More particularly, the compounds of the present invention have the formulas

B

6

wherein R in these and succeeding formulas may be any of the previously enumerated radicals, respectively, except 5-nitro-2-furyl.

45 These novel compounds, and especially those in which R in formula B is haloloweralkyl, are active antibacterial and antifungal agents. For this reason, they can be employed in disinfectant compositions to control a variety of microorganisms such as *Salmonella typhimurium*, *Escherichia coli*, *Proteus vulgaris*, and *Alternaria* species. In such use, the compounds are dispersed on an inert solid or in a suitable liquid (preferably water) and applied as a dust or spray. In a representative operation, good control of the above-named organisms was obtained when the compound wherein R is chloromethyl in the general formula above was employed in an aqueous medium at a concentration of about 50 parts per million. The new compounds are also effective against *Trichomonas vaginalis* when applied topically in concentrations of 50 parts per million or less.

DETAILED DESCRIPTION

The compounds of the present invention may be prepared by the reaction of equimolar proportions of a 5-nitro-2-furoyl halide (preferably the chloride) and a compound of the formula

in the presence of an inert solvent such as acetone and a hydrohalide acceptor such as potassium carbonate. Good results are obtained when the R-substituted amidoxime and hydrohalide acceptor are dissolved in the solvent.

In like manner, the reaction of any R-substituted amidoxime wherein R is as hereinbefore indicated with a 5-nitro-2-furoyl halide will evolve hydrohalide of reaction and result in the formation of the corresponding R-substituted 5-nitro-2-furoylamidoximes. Representative of such compounds considered to be within the scope of this invention are:

- O-(5-nitro-2-furoyl)-benzamidoxime melting at 170° C.
- O-(5-nitro-2-furoyl)-formamidoxime
- O-(5-nitro-2-furoyl)-bromoacetamidoxime
- O-(5-nitro-2-furoyl)-acetamidoxime
- O-(5-nitro-2-furoyl)-isobutyramidoxime
- O-(5-nitro-2-furoyl)-valeramidoxime
- O-(5-nitro-2-furoyl)-2-carboxamidoacetamidoxime
- O-(5-nitro-2-furoyl)-N-benzoylaminooacetamidoxime
- O-(5-nitro-2-furoyl)-cyanoacetamidoxime
- O-(5-nitro-2-furoyl)-phenylacetamidoxime
- O-(5-nitro-2-furoyl)-t-butylaminooacetamidoxime
- O-(5-nitro-2-furoyl)-diethylaminooacetamidoxime

- O-(5-nitro-2-furoyl)-phenoxyacetamidoxime
- O-(5-nitro-2-furoyl)-carboxyoxalamidoxime
- O-(5-nitro-2-furoyl)-carbomethoxyoxalamidoxime
- O-(5-nitro-2-furoyl)- β -carbomethoxypropionamidoxime
- O-(5-nitro-2-furoyl)-o-chlorobenzamidoxime
- O-(5-nitro-2-furoyl)-p-methoxybenzamidoxime
- O-(5-nitro-2-furoyl)-o-methylthiobenzamidoxime

The R-substituted amidoximes employed as one of the starting materials are known compounds or can be readily prepared by refluxing equimolar amounts of an alkali metal hydroxide, hydroxylamine hydrochloride and a nitrile of the formula R—C≡N in an inert solvent such as ethanol. The solution is then filtered and the filtrate concentrated to recover the desired amidoxime as a residue which can be purified by recrystallization from a suitable solvent.

Using methods exemplified in the foregoing examples, the following compounds, wherein R refers to substitutions in Formula B, were made.

EXAMPLE 34

5-nitro-2-furamidoxime O-aceturate

Ten grams (0.0875 mole) of N-acetylglycine is dissolved in 100 ml. of acetone containing 8.86 g. (0.0875 mole) of triethylamine. Maintaining anhydrous conditions with chilling and stirring, 9.49 g. (0.0875 mole) of ethyl chloroformate in 25 ml. of acetone is added dropwise. The resulting mixture is stirred for 4 hours and then filtered to remove the triethylamine hydrochloride. The filtrate is added dropwise with stirring to a solution of 15 g. (0.08757) of 5-nitro-2-furylamidoxime in 200 ml. of acetone. After addition, the solution is heated at 40° overnight with stirring. Chilling and filtering the reaction mixture gives 11.77 g. (49.7%) of crude products, M.P. 181°-183° dec. Purification in nitromethane gives a pure product melting at 196°-198° dec. weighing (48.2%).

EXAMPLE 35

5-nitro-2-furamidoxime O-2(acetylthio)-acetate

17.9 g. (0.1045 mole) of 5-nitro-2-furylamidoxime is dissolved in 450 ml. of acetone containing 21.6 g. (0.1045 mole) of N,N-dicyclohexylcarbodiimide. Maintaining anhydrous conditions and with stirring, a solution of 14 g. (0.1045 mole) of acetylmercapto acetic acid in 50 ml. of acetone is added dropwise. The resulting reaction mixture is allowed to stir overnight at room temperature. After removal of N,N-dicyclohexylurea by filtration, the filtrate is concentrated to yield 33.6 g. (100%) of crude product, M.P. 140°-143° dec. Crystallization from ethanol gave 16.95 g. (56.5%) of product, M.P. 162°-163° dec.

EXAMPLES 36-44

35 Using the methods of the foregoing examples, the following compounds of Formula C were made.

Example	R	Mol. wt.	Melting point, °C.
36		348.16	104-106
37		432.32	98-100
45		488.42	106-108

54	10	100	1,000

Additionally, the compound of Example 46 has been found to have good activity against *Trichomonas*

vaginalis in mice. When administered orally at a dosage level of 500 mg./kg., 50 percent of the parasites were killed. At a dosage level of 750 mg./kg., administered orally, from 60-78 percent of the parasites were killed.

40 The LD₅₀ when administered intraperitoneally was found to be 750 mg./kg. When administered orally to mice at the LD₅₀ level, no deaths occurred. The compound of Example 48 was likewise found to have activity against *Trichomonas vaginalis* in mice. When administered orally at a dosage level of 500 mg./kg., from 56 to 78 percent of the parasites were killed, the LD₅₀ for oral administration being 750 mg./kg.

45 What is claimed is:

50 1. A compound of the formula:

55 wherein R is a member of the group consisting of hydrogen, loweralkyl, chloromethyl, bromomethyl, phenyl, phenylalkyl, phenoxyloweralkyl, loweralkylaminoloweralkyl, dialkylaminoloweralkyl, carboxy, carboloweralkoxy, carboloweralkoxyloweralkyl, acarboxamidoloweralkyl, 60 acylaminoloweralkyl, halophenyl, alkoxyphenyl, hydroxyphenyl, cyanoloweralkyl, acylaminophenyl, loweralkylthiophenyl, nitrophenyl, aminophenyl, sulfonamido-phenyl, nitrophenylloweralkyl, halophenylloweralkyl, loweralkylphenyl, diloweralkoxyphenylloweralkyl, loweralkylhalophenyl, N-acyl-N-cycloalkyaminoloweralkyl, N-acyl - N - loweralkylaminoloweralkyl, N-acyl-N-phenylaminoloweralkyl, N-acyl-N'-diloweralkylaminoloweralkylaminoloweralkyl, haloacylaminoloweralkyl, N,N-dialkyl-N-(phenylloweralkyl)-loweralkyl, ammonium chloride, 65 N,N-dialkyl-N-(dihalophenylloweralkyl), loweralkyl ammonium chloride, morpholinoloweralkyl, piperidinoloweralkyl, pyrrolidinoloweralkyl, and wherein "acyl" is a member of the group consisting of the benzoyl and acetyl radicals and wherein both "loweralkyl" and "alkyl" are limited to 1 to 5 carbon atoms.

70 75

11

2. A compound as claimed in claim 1 wherein R is a member of the group consisting of N-acetyl-N-methyl-aminomethyl and N-acylaminoloweralkyl.

3. A compound as claimed in claim 1 wherein R is a member of the group consisting of chloromethyl, bromomethyl, p-sulfonamidophenyl, phenyl, p-aminophenyl, nitrophenyl, N,N-dimethyl-N-benzylmethylammonium, p-methoxyphenyl, p-chlorophenylmethyl, dimethylaminomethyl, morpholinomethyl, N-acetyl, N-cyclohexylaminomethyl, and N-acetylaminomethyl.

4. A method for the preparation of a compound of the formula:

wherein R is a member of the group consisting of hydrogen, loweralkyl, chloromethyl, bromomethyl, phenyl, phenylalkyl, phenoxyloweralkyl, loweralkylaminoloweralkyl, dialkylaminoloweralkyl, carboxy, carboloweralkoxy, carboloweralkoxyloweralkyl, carboxamidoloweralkyl, acylaminoloweralkyl, halophenyl, alkoxyphenyl, hydroxyphenyl, cyanoloweralkyl, acylaminophenyl, loweralkylthiophenyl, nitrophenyl, aminophenyl, sulfonamidophenyl, nitrophenylloweralkyl, halophenylloweralkyl, loweralkylphenyl, diloweralkoxyphenylloweralkyl, loweralkylhalophenyl, N-acyl-N-cycloalkylaminoloweralkyl, N-

12

acyl - N - loweralkylaminoloweralkyl, N-acyl-N-phenylaminoloweralkyl, N-acyl-N'-diloweralkylaminoloweralkylaminoloweralkyl, haloacylaminoloweralkyl, N,N-dialkyl-N-(phenylloweralkyl)-loweralkyl ammonium chloride, N, N - dialkyl - N - (dihalophenylloweralkyl) - loweralkyl ammonium chloride, morpholinoloweralkyl, piperidino-loweralkyl, pyrrolidinoloweralkyl, and wherein "acyl" is a member of the group consisting of the benzoyl and acetyl radicals and wherein both "loweralkyl" and "alkyl" are limited to 1 to 5 carbon atoms; which comprises: reacting a carboxylic acid with a reactant comprising an admixture of an alkylchloroformate and a mineral acid acceptor to produce an active intermediate; condensing an amidoxime with said active intermediate; and recovering the product formed.
